UNITED STATES PATENT OFFICE.

WILL P. HAYNES, OF CORTLAND, NEW YORK.

DESIGN FOR A MUSIC-RACK.

SPECIFICATION forming part of Design No. 20,168, dated September 23, 1890.

Application filed July 17, 1890. Serial No. 350,094. Term of patent 7 years.

To all whom it may concern:

Be it known that, I, WILL P. HAYNES, of Cortland, in the county of Cortland and State of New York, have invented new and useful improvements in Designs for Music-Racks, of which the following, taken in connection with the accompanying drawings, is a full, clear, and exact description.

Figure 1 is a front elevation of my newly-designed music-rack. Fig. 2 is an end view thereof.

The leading feature of my design consists in a music-rack having lyre-shaped sides.

A A are the sides of the rack, constructed lyre-shaped, as shown in the drawings.

a a are the feet thereof. Between the two upper arms of the lyre is a cross-bar 2, pro-

vided with ornamented screw-heads 4, and vertical bars 3, representing the strings of a lyre.

What I claim as my invention, and desire to secure by Letters Patent, is—

The design for a music-rack, as herein described and shown, consisting of the lyre-shaped sides A, having feet a, cross-bars 2, provided with ornamented screw-heads 4, and vertical bars 3.

In witness whereof I have hereunto set my hand this 30th day of June, 1890.

WILL P. HAYNES.

In presence of—

H. P. DENISON,
C. W. SMITH.
